UNITED STATES PATENT OFFICE.

GEORGE W. SISK, OF KANSAS CITY, MISSOURI, ASSIGNOR TO JOHN W. MASHBURN, OF KANSAS CITY, MISSOURI.

DESIGN FOR A DOLL OR STATUETTE.

61,176.

Specification for Design.

Patented July 4, 1922.

Application filed March 27, 1922. Serial No. 1,411. Term of patent 3½ years.

To all whom it may concern:

Be it known that I, GEORGE W. SISK, a citizen of the United States, residing at Kansas City, county of Jackson, State of Missouri, have invented a new, original, and ornamental Design for a Doll or Statuette, of which the following is a specification, reference being had to the accompanying drawing, forming a part thereof.

In the drawing—

I claim:

The ornamental design for a doll or statuette, as shown.

GEORGE W. SISK.
